DOUBLE CASING PUMP

Edward J. Blackwell, Wauwatosa, Wis., assignor
to Allis-Chalmers Manufacturing Company,
Milwaukee, Wis., a corporation of Delaware

Application October 26, 1949, Serial No. 123,719

4 Claims. (Cl. 103—109)

1

This invention relates to multiple stage double casing pumps. More specifically this invention relates to that type of double casing pump especially designed for pumping liquids at relatively high pressure. The principal object of this invention is the provision of a new and improved liquid pumping machine.

The double casing type pump generally comprises an inner pumping casing spaced within an outer pressure casing. The outer casing is generally divided by an annular projection into an intake chamber and a discharge chamber. The inner casing is fitted within the outer casing and is seated against the annular projection. The inner casing contains impellers mounted within annular passages that direct the liquid through a series of pumping stages, finally passing into the discharge chamber of the outer casing. The inner casing is held tight against the annular seat by the discharge pressure within the discharge chamber.

The pumping stages are usually so arranged that the first stage takes suction from the intake chamber and discharges to the second stage intake located at the opposite end of the inner casing. This arrangement helps to simplify the problem of sealing the pressure end of the inner casing, since the seal need only resist the discharge pressure of the first stage.

Another serious problem, that of vapor formation, is presented when a pump of this type is used to pump liquids that are highly volatile either by the very nature of the liquid, or because of the high temperature or low suction pressure at which the liquid must be handled. The flow of liquid into the first stage from the intake chamber must be at a rate sufficient to satisfy the demand in order to prevent the formation of a partial vacuum or a reduction in pressure that will cause vapor to form, thus impairing the efficiency of the machine. Accordingly, a primary object of the invention is to take in liquid from the intake chamber at a relatively low velocity and satisfy the demand without the formation of vapor.

Another object of the invention is to prevent liquid from a higher pressure stage leaking into the intake chamber and flashing into vapor at the reduced pressure and thereby vapor locking the first stage intake.

Objects and advantages other than those above set forth will be apparent as the description of the invention proceeds.

The novel features of the invention and how the objects are attained will appear from this specification and the accompanying drawing.

2

showing an embodiment of the invention and forming a part of this application, and all these novel features are intended to be pointed out in the claims.

Referring to the drawing, the pump comprises an outer casing 10 divided into an intake chamber 11 and a discharge chamber 12 separated by an annular projection 13. An inlet passage 14 transmits liquid at intake pressure to the intake chamber 11. A discharge passage 15 transmits the liquid from the discharge chamber 12 at discharge pressure. The outer casing 10 is open at the discharge chamber 12 end of the casing. This open end is fitted with a casing cover 16 which is attached to the outer casing 10 by means of bolts 17, and a liquid tight seal is insured by a gasket 20 which is set in a recess 21 to avoid the possibility of blowing out. An inner casing 22 is inserted into the open end 10 of the outer casing 10 and mounted therein. The radial shoulder 23 of the inner casing 22 is seated against the annular projection 13 within the outer casing 10. The inner casing 22 is held firmly against the projection 13 by the discharge pressure of the liquid within the discharge chamber 12. A gasket 24 is fitted between the shoulder 23 and the projection 13 to provide a liquidtight seal between the intake chamber 11 and the discharge chamber 12. Bolts 25 provide an initial seal and keep the inner casing 22 in position during periods of starting and stopping when the pressure within the discharge chamber 12 may not be enough to maintain the seal. Keys 26, 27 also aid in supporting the inner casing 22 in proper alignment, in that they keep the inner casing 22 from turning within the outer casing 10.

A shaft 28 is disposed in the inner casing 22 and extends through both ends of the outer casing 10. A series of annular passages 29 to 35 direct the fluid through the inner casing 22. Impellers 36 to 43 are mounted on the shaft in the annular passages 29 to 35.

The pressure of the fluid as it passes through the inner casing 22 is raised in a series of stages herein numbered 1 through 7. The first stage comprises two impellers 36, 37 both of which take suction from the intake chamber 11 and discharge into the passages 29 which direct the liquid to the opposite end of the inner casing 22, where the liquid enters stage 2. The liquid is then directed through the remainder of the stages 2 to 7, which have a single impeller 38 to 43 in each, and the path of the liquid is indicated by the passages numbered 30 to 35. The fluid passes from the final pumping stage 7 to

the passage 35 which discharges into the pressure chamber 12 of the outer casing 10, and the fluid is then discharged from the pump through the discharge passage 15. The axial thrust of the impellers is negated by having an equal number of the impellers facing each end of the pump.

The two impellers 36, 37, both taking suction from the intake chamber 11, are used as the first pumping stage so that a relatively low eye speed at the entrance of the impeller will be maintained. The flow of liquid must keep up with the demand of the first stage at all times to prevent a reduction in pressure of partial vacuum, which may cause the liquid to vaporize, thereby affecting the operating characteristics of the machine.

The arrangement and location of these two impellers 36, 37 is important in the elimination of all dangers of vapor formation. The impeller 37 is within the inner casing 22 and is wholly within the discharge chamber 12 of the outer casing 10. The inlet of the impeller 37 faces the intake chamber 11 and taking suction therefrom discharges into the passage 29. The passage 29 is at this point adjacent to the passage 32 having fourth stage pressure therein. The passages 29 and 32 are separated by an annular shaft seal 81. Any leakage of fourth stage pressure that does escape the shaft seal 81 will leak into the passage 29 having first stage pressure. Liquid under fourth stage pressure will not therefore be able to find its way into the intake chamber 11 where the pressure is substantially less than first stage and where there is danger of such liquid flashing into a vapor at the reduced pressure and vapor locking the first stage intake.

The impeller 36 is mounted within an extending portion 70 of the inner casing 22 and is within the intake chamber 11 of the outer casing 10. A stuffing box member 71 is fitted about the shaft 28 to the outer casing 10 and extends through the outer casing 10 into the intake chamber 11. An annular sleeve 72 extending from the portion 70 embraces the stuffing box member 71, thereby supporting the portion 70 in proper axial alignment about the impeller 36.

The arrangement and number of stages as illustrated results in having between stage 1 and stage 5, fourth stage pressure in the fluid passage 32 adjacent the passage 29 having first stage pressure therein, and between stage 1 and stage 4, seventh stage pressure in the passage 35 adjacent the passage 32 having fourth stage pressure therein. The high differential in pressure at these two locations requires suitable high pressure seals 81, 82 to reduce leakage of the high pressure liquid into the passage of lower pressure, resulting in a loss of pump efficiency. The construction of these high pressure sealing arrangements 81, 82 may be of the form as here shown and more fully described and claimed in the copending application of Milton W. Lutz, Serial No. 123,856, filed October 26, 1949.

A special stuffing box arrangement is provided, as here shown, for sealing the inner casing 22 to the shaft 28 and to the end cover 16. This arrangement will allow axial expansion of the inner casing 22 relative to the outer casing 10 in response to changes in pressure and/or temperature within the inner casing 22. When a pump of this general type is used for pumping liquid at high temperature such as boiler feed water, the axial movement of the inner casing 22 relative to the outer casing 10 may be quite

substantial and frequent as changes in demand are made upon the pump. To permit this relative movement and yet maintain an effective seal, an annular member 51 is fitted to the inner casing 22 and extends through an opening 60 in the end cover 16. Glands 52, 53 and packing 55, 56 placed concentrically about and within the member 51 thereby effect a seal between member 51 and the end cover 16, and between the member 51 and the shaft 28. Bolts 61, 66 keep the glands 52, 53 drawn up tight on the packing 55, 56 to maintain the seal at all times. This stuffing box arrangement is described and claimed in the copending application of Hugh L. Ross, Serial No. 123,768, filed October 26, 1949. It will be understood that as far as the invention of the present application is concerned, means of other form may be provided for sealing the inner casing 22 to the shaft 28 and to the cover 16.

From the foregoing it will be apparent to those skilled in the art that the illustrated embodiment of the invention provides a new and improved liquid pumping machine and accordingly accomplishes the objects of the invention. On the other hand, it will also be obvious to those skilled in the art that the illustrated embodiment of the invention may be variously changed and modified, or features thereof, singly or collectively, embodied in other combinations than those illustrated, without departing from the spirit of the invention, or sacrificing all of the advantages thereof, and that accordingly the disclosure herein is illustrative only, and the invention is not limited thereto.

It is claimed and desired to secure by Letters Patent:

1. A centrifugal pump comprising: an outer casing having an inlet passageway and an outlet passageway for the flow of liquid therethrough and having an internal wall portion defining an opening; an inner casing in said outer casing co-operating with said wall portion to close said opening and divide said outer casing into separate intake and discharge chambers respectively communicating with said inlet and discharge passageways, said inner casing comprising first, second and third wall parts, said first wall part defining a plurality of compartments and intake passages for said liquid, each said compartment communicating with the intake passage hydraulically adjacent thereto and the last of said compartments communicating with said outlet passageway, said second wall part cooperating with said first wall part to define an intermediate passage contiguous to said second wall part and communicating with one of said compartments, said third wall part cooperating with said second wall part to define a pair of compartments on the intake chamber side of said second wall part, one compartment of said pair being contiguous to said second wall part and both compartments of said pair communicating with one of said intake passages, a shaft supported for rotation in said inner casing and extending through said wall parts; sealing means interposed between said shaft and said second wall part; a plurality of single impellers mounted on said shaft, said single impellers being operatively disposed for rotation in said compartments of said first wall part to develop predetermined positive liquid pressures therein and in said intermediate passage, and a pair of impellers mounted on said shaft on the intake chamber side of said second wall part, one impeller of said pair of impellers being oper-

atively disposed in one compartment of said pair of compartments and the other impeller of said pair of impellers being operatively disposed in the other compartment of said pair of compartments, said pair of impellers cooperating to reduce the velocity of liquid flow into said pair of compartments below the velocity of flow in said intake passages and to develop a predetermined liquid suction pressure in said intake chamber and a predetermined intermediate liquid pressure in said pair of compartments greater than said suction pressure, said intermediate pressure cooperating with said sealing means to substantially prevent back liquid flow from said intermediate passage to said intake chamber.

2. A centrifugal pump comprising: an outer casing having an inlet passageway and an outlet passageway for the flow of liquid therethrough and having an internal wall portion defining an opening; an inner casing in said outer casing cooperating with said wall portion to close said opening and divide said outer casing into separate intake and discharge chambers respectively communicating with said inlet and discharge passageways, said inner casing comprising first, second and third wall parts, said first wall part defining a plurality of compartments and intake passages for said liquid, each said compartment communicating with the intake passage hydraulically adjacent thereto and the last of said compartments communicating with said outlet passageway, said second wall part cooperating with said first wall part to define an intermediate passage contiguous to said second wall part and communicating with one of said compartments, said third wall part cooperating with said second wall part to define a pair of compartments on the intake chamber side of said second wall part, one compartment of said pair being contiguous to said second wall part and both compartments of said pair communicating with one of said intake passages, a shaft supported for rotation in said inner casing and extending through said wall parts; sealing means interposed between said shaft and said second wall part; a plurality of single impellers mounted on said shaft, said single impellers being operatively disposed for rotation in said compartments of said first wall part to develop predetermined positive liquid pressures therein and in said intermediate passage, the axial thrust of each of said single impellers in said compartments being balanced by another of said single impellers in said compartment in said first wall part mounted to face in the opposite direction, and a pair of impellers mounted on said shaft on the intake chamber side of said second wall part, one impeller of said pair of impellers being operatively disposed in one compartment of said pair of compartments and the other impeller of said pair of impellers being operatively disposed in the other compartment of said pair of compartments, said pair of impellers cooperating to reduce the velocity of liquid flow into said pair of compartments below the velocity flow in said intake passages and to develop a predetermined liquid suction pressure in said intake chamber and a predetermined intermediate liquid pressure in said pair of compartments greater than said suction pressure, said intermediate pressure cooperating with said sealing means to substantially prevent back liquid flow from said intermediate passage to said intake chamber.

3. A centrifugal pump comprising: an outer

casing having an inlet passageway and an outlet passageway for the flow of liquid therethrough and having an internal wall portion defining an opening; an inner casing in said outer casing cooperating with said wall portion to close said opening and divide said outer casing into separate intake and discharge chambers respectively communicating with said inlet and discharge passageways, said inner casing comprising first, second and third wall parts, said first wall part defining a plurality of compartments and intake passages for said liquid, each said compartment communicating with the intake passage hydraulically adjacent thereto and the last of said compartments communicating with said outlet passageway, said second wall part cooperating with said first wall part to define an intermediate passage contiguous to said second wall part and communicating with one of said compartments, said third wall part cooperating with said second wall part to define a pair of compartments on the intake chamber side of said second wall part, one compartment of said pair being contiguous to said second wall part and both compartments of said pair communicating with one of said intake passages, a shaft supported for rotation in said inner casing and extending through said wall parts; sealing means interposed between said shaft and said second wall part; a plurality of single impellers mounted on said shaft, said single impellers being operatively disposed for rotation in said compartments of said first wall part to develop predetermined positive liquid pressures therein and in said intermediate passage, and a pair of impellers mounted on said shaft on the intake chamber side of said second wall part and having inlets facing and cooperating with each other to balance the thrust developed by each of said pair of impellers, one impeller of said pair of impellers being operatively disposed in one compartment of said pair of compartments and the other impeller of said pair of impellers being operatively disposed in the other compartment of said pair of compartments, said pair of impellers cooperating to reduce the velocity of liquid flow into said pair of compartments below the velocity of flow in said intake passages and to develop a predetermined liquid suction pressure in said intake chamber and a predetermined intermediate liquid pressure in said pair of compartments greater than said suction pressure, said intermediate pressure cooperating with said sealing means to substantially prevent back liquid flow from said intermediate passage to said intake chamber.

4. A centrifugal pump comprising: an outer casing having an inlet passageway and an outlet passageway for the flow of liquid therethrough, and having an internal wall portion defining an opening; an inner casing in said outer casing cooperating with said wall portion to close said opening and divide said outer casing into separate intake discharge chambers, respectively, communicating with said inlet and discharge passageways, said inner casing comprising first, second and third wall parts, said first wall part defining a plurality of compartments and intake passages for said liquid, each said compartment communicating with the intake passage hydraulically adjacent thereto and the last of said compartments communicating with said outlet passageway, said second wall part cooperating with said first wall part to define an intermediate passage contiguous to said second wall part and

communicating with one of said compartments, said third wall part cooperating with said second wall part to define a pair of compartments on the intake chamber side of said second wall part, one compartment of said pair being contiguous to said second wall part and both compartments of said pair communicating with one of said intake passages, a shaft supported for rotation in said inner casing and extending through said wall parts; sealing means interposed between said shaft and said second wall part; a plurality of single impellers mounted on said shaft, each of said plurality of single impellers having a predetermined capacity, said single impellers being operatively disposed for rotation in 15 said compartments of said first wall part to develop predetermined positive liquid pressures therein and in said intermediate passage, and a pair of impellers mounted on said shaft on the intake chamber side of said second wall part, 20 each of said pair of impellers having a capacity less than said predetermined capacity, one impeller of said pair of impellers being operatively disposed in one compartment of said pair of compartments and the other impeller of said pair of impellers being operatively disposed in the

5
10

other compartment of said pair of compartments, said pair of impellers cooperating to reduce the velocity of liquid flow into said pair of compartments below the velocity of flow in said intake passages and to develop a predetermined liquid suction pressure in said intake chamber and a predetermined intermediate liquid pressure in said pair of compartments greater than said suction pressure, said intermediate pressure cooperating with said sealing means to substantially prevent back liquid flow from said intermediate passage to said intake chamber.

EDWARD J. BLACKWELL.
